SAFETY ALARM SYSTEM

Louis Santino, Brooklyn, N. Y.

Application January 6, 1939, Serial No. 249,594

8 Claims. (Cl. 177—314)

This invention relates to safety alarm systems applicable to buildings or enclosures of all types wherein protection is sought against burglary, fire, poisonous gases and the like. More specifically the invention relates to a radio transmitting safety alarm system provided with automatic signalling means. The invention has particular utility in connection with buildings in cities provided with central police and fire stations and equipped for the reception of radio signals.

Heretofore in radio alarm signalling systems certain disadvantages have been present such as too great difficulty of adjustment, lack of positiveness in the operation of the transmitting apparatus, lack of provision for variation in line voltage of the power circuits, lack of adequate equipment to take care of various abnormal disturbances such as that arising from escaping gas, and other deficiencies.

It is accordingly an object of the present invention to provide a transmitting system which is positive in its operation, and which automatically restores the apparatus to signalling position should a temporary drop in the line voltage cause an energization of the signalling apparatus; to provide means in a common electrical system for transmitting alarms arising from window or door tampering, or from fire; and to provide a novel and automatic device sensitive to the action of gases for turning on a gas alarm and subsequently restoring itself to condition for taking on new signals. Still another object of the invention is to provide an alarm system which transmits signals, indicating window or door tampering, noiselessly and without warning to the building occupants. A further object is the provision of a transmitting system which continues its alarm after the initial energization until authorized persons, such as the police, arrive to terminate the signal. An object also is to provide a safety alarm system which transmits voice as well as automatic signals.

Further objects will become apparent on inspection of the following specification describing an arrangement and system which may be preferred and which is further set forth in the accompanying drawing in which is shown the wiring system and the various parts including the radio transmitter system, the automatic signal restoring device, the code disc mechanism, the thermostatic element, and the gas detecting device in diagrammatic perspective, section or plane.

The invention contemplates the use of a radio transmitter electrically connected to a closed circuit system which when applied to a building in-

cludes contacts opened and closed by the movement of windows and doors so that when these elements are opened the closed circuit is broken, thus setting off certain automatic code devices which through the transmitter are broadcast through the central receiving station, the automatic code indicating the location of the building and the nature of the disturbance, such as burglary in the example mentioned. In the case of fire the closed circuit is opened by a heat responsive element such as a thermostatic switch or a fuse. In the case of gas the switch is opened by an automatic gas detecting device. In each case mentioned, that is, burglary, fire and gas leakage, different code messages are transmitted to indicate at the receiving station the type of disturbance at the given location.

In the drawing,

Fig. 1 is a wiring diagram showing the signalling unit; and

Fig. 2 is a wiring diagram showing the contact restoring unit.

Referring to Fig. 1, the power mains are indicated at 1 and 2 deriving from the usual 110 volt alternating current power system between the building meters and fuse box, thus being independent of fuse blowouts. Adaptation to direct current may also be made. The power circuit leads through main circuits 10 and 11 to the transformer 12, the secondary of which connects in series through separable electrical contacts 14 positioned at various windows, doors or other openings of the building in such manner that opening of the windows or doors will cause disconnection in the transformer circuit. A master switch 15 short circuits the various window and door contacts 14, this switch being preferably operated by the key of the main or final exit door lock, the action being that when the door is locked the switch 15 is opened, and when the lock is opened the switch 15 is closed, short circuiting the door and window contacts and permitting free use of the windows and other exits without producing an alarm signal. The circuit 13 including the secondary of transformer 12 may also include other separable contacts as 16 and 17 which are also in series with contacts 14.

The secondary transformer circuit 13 includes in series also the electromagnet 18 having a metal core 19 projecting at either end as shown. Pivotaly positioned adjacent the ends of the electromagnet core 19 are armatures 20 and 21 which are normally held by springs 22 and 23 away from the magnet core in open position. In this displaced position

of the armatures 20 and 21 they are adapted to connect with contacts 24 and 25. When armature 20 engages contact 24 it energizes the motor 3 operating the code device 4 through the gear reduction 5; the power pack 6 and radio transmitter and receiver 7 are also energized. When armature 21 engages contact 25 it closes the circuit through the code device 4, thus energizing the modulating circuits in the transmitter and making effective the transmission of the code to the receiving station.

The circuit for energizing the power supply of the transmitter and the motor of the code device leads from the wire 11 through wire 26 to the armature 20, contact 24, wire 27, wire 28 to the motor, wire 29 from the motor, and wire 10 to the power main 1. Also, from wire 27 the circuit branches through wire 30 to the transmitter power supply 6 and transmitter 7, returning through wire 31 to the outlet main 10.

In the code disc circuit, from the contact 25 of armature 21, wire 32 connects to the brush 33 on the rotatable disc 34, the periphery of which is formed with teeth 35 so as to give the desired sequence of signals indicative of the source of the same. The circuit leads from the brush to the disc to the hub 36 and thence through the hub contact 37, wire 38, code key 39, speech-code switch 40, the primary of transformer 41, wire 42, battery 43 to the ground 44. This circuit also includes the secondary of transformer 41 connected at one end to the C battery and at the other to the grid of the modulator tube 45, the plate of which connects to the transformer 46. The secondary of the transformer 46 connects at one end to the high B battery terminal and at the other end to the amplifying and transmitter unit 7.

The oscillator tube is indicated by the numeral 40 52, the plate of which is connected to one side of the primary of the transformer 53, the other side of which is connected to the B+ terminal. The grid circuit of tube 52 connects to one side of the secondary, the other side passing through the wire 54 to the armature 21 of the burglar alarm circuit. A wire 55 provided with a switch 56 is connected across wires 38 and 54 of the oscillator circuit to short circuit the same when code messages are being transmitted. The oscillator circuit is preferably operable on a thousand cycles and the transmitter on a wave length preferably of ten meters and a power output of at least five watts.

The transmitter is also provided with mechanism to transmit voice, operative through the modulator tube circuit consisting in the voice transmitter 50 which is in the grounded circuit 51 connected to the two-way switch 40. While primarily designed for transmission, the transmitter is also adapted for reception so that signals or voice may be both sent and received by the apparatus. In the operation of the device for transmission when code messages are being sent, switch 56 of the short circuit 55 is closed, as well as code key 39, and two-way switch 40 connects the circuit 38 to the circuit of transformer 41. When voice is to be transmitted switch 40 connects with the telephone circuit 51 and short circuiting switch 56 is closed to permit voice transference.

In the operation of the burglar alarm system as hereinabove described, normally the armatures 20 and 21 of electromagnet 18 controlling the burglar alarm circuit are in contact with the core 19 of the electromagnet, thereby opening the cir-

cuits through contacts 24 and 25. With these contacts open the motor 3 and the transmitter are de-energized and the circuit including the code disc is opened. Should, however, any of the door or window contacts 14, 16 or 17 be opened 5 the electromagnet 18 is de-energized, the springs draw the armatures 20 and 21 away from the magnet core closing the circuits through contacts 24 and 25, thereby energizing the motor 3 and the transmitter and producing code signals through 10 the disc 34 which are immediately transmitted to the receiving station. The signal is transmitted continuously until there is a response on the part of police or other authorized persons who are provided with a key to operate mechanism for 15 moving the armatures 20 and 21 into engagement with the electromagnet core 19, thereby breaking the alarm circuit. This can be done, however, only after the contacts 14, 16 and 17 are closed so as to provide a closed circuit to the power 20 source. The mechanism for moving the armatures into contact with the magnet core will be described hereinafter.

Connected in parallel to the burglar alarm circuit including the electromagnet 18 is the gas 25 alarm circuit including the electromagnet 60. As shown in the drawing, wire 61 connects one terminal of the secondary of the power transformer 12 to the electromagnet 60. The other terminal of the electromagnet 60 is connected directly to 30 the gas detecting device 63, the return circuit 64 of which passes through the hand switch 65 to the other terminal of the secondary of the transformer 12. The gas detecting device 63 is provided with a casing including a stationary base 35 section 66 and an upper or top movable section 67. The base section 66 may be circular in shape and provided with an annular up-turned flange 68 with an inwardly bent edge flange 69. The upper casing section 67 is cup shaped, consisting of an upper disc 70 and a lower depending wall 71 provided with an outwardly extending edge flange 72, the latter being adapted to engage the flange 69 of the base section of the casing on its under side, thereby permitting a limited movement of the upper casing and providing a stop at either end of the path of movement thereof. The casing may be formed of gas permeable substances, and with openings 73 to permit easy ingress of gases into the casing. A perforated box 50 170 encloses the casing 66 and 67.

Within the casing and mounted on the base section 66 at approximately the center thereof is an electromagnet 74 which in turn is provided with a movable core 75. The upper end of the core 75 is permanently attached to the under side of the upper disc 70 of the top casing section 67 and is accordingly movable therewith. A spring 76 is interposed between the base of the movable core 75 and the base section 66 for the purpose of holding the armature normally at its upper position with its flange edges 72 contacting against the base section flange 69. The support 77 at the upper end of the electromagnet 74 pivotally carries the spring pressed contact arm 78, 60 the end of which detachably engages the fixed contact member 79. A depending finger 80 fastened to the under side of the casing plate 70 directly above the contact arm 78 is adapted to engage the same under certain circumstances, as 70 will hereinafter be pointed out.

Also included within the casing 63 is a gas sensitive element or thermostat 81 consisting of two metal plates 82 and 83 supported on the base section 66. Plate 82 is provided at its upper end 75

with a contact 84 which is adapted to engage normally the coating contact member 85. The plates 82 and 83 are of different metal and consequently of different coefficients of heat expansion so that when subjected to heat the contacts 84 and 85 separate, the contacts re-engaging when the temperature of the thermostat is reduced to normal or room temperature. Any metal may be used provided there is a sufficiently marked difference of heat coefficient between the two metals; however, I prefer to use brass for plate 82 and iron for plate 83. An adjusting screw 86 is provided for the contact 84 so that accommodation for seasonal temperature changes may be made.

Wound around the two plates 82 and 83 is a fine coil of wire 87 which is highly absorbent of gases such as illuminating or fuel gases and particularly carbon monoxide, and which in the process of absorption of these gases becomes heated. I prefer palladium wire in this connection. It will now be apparent that when gases containing carbon monoxide, for example, are absorbed by the palladium wire the resultant heat will cause expansion of the brass plate with reference to the iron plate, thereby resulting in a disengagement of the contacts 84 and 85. The electrical circuits of the gas detector 63 may be traced from the wire 64 to the contact plate 78, contact 79, wire 88, stationary contact 85, thermostat contact 84 and wire 89 connecting to the wire 62 of electromagnet 60. Forming a bridging connection between wires 62 and 64 is a condenser 90, the purpose of which is to aid in the prevention of spark formations when the contacts of the device separate. Also connected across the wires 62 and 64 in parallel with the contact circuits is the electromagnet 74.

The operation of the gas detector is as follows: Normally the electromagnet 74 lies in the closed circuit through the electromagnet 60 and the secondary 13 of transformer 12. The degree of energization, however, is weak since the magnet is short circuited by the contact circuit and hence the spring 76 holds the core 75 at the limit of its movement. Should, however, gas leakage occur and penetrate into the casing 63 the palladium wire becomes heated, thereby energizing the thermostat 81, causing an opening of contacts 84 and 85 and energizing strongly the electromagnet 74. Thereupon the core 75 moves downwardly into the electromagnet, bringing down the upper casing 67 until its base flange 72 contacts against the base 66. In this downward movement the finger 80 contacts with the arm 78 breaking the contact at 79. Should the gas now be removed from the vicinity of the detector the thermostat 81 will flex into normal position, restoring electrical connection between contacts 84 and 85. However, the contact between 78 and 79 will still be open since the electromagnet is energized and will continue to be open until some authorized person applies a key to open switch 65. Thereupon the core 75 with its casing armature is released and contacts 78 and 79 are closed so that when switch 65 is again closed the magnet 74 is short circuited by the contact circuit. The device is now in condition for repeating its signal.

When the magnet 74 is initially energized by the breaking of the thermostat contacts 84, 85, circuits are closed to the motor 3, the code signal device 4, transmitter 7 and the circuit of code wheel 91. The circuits for accomplishing these results are as follows: Adjacent the core 92 of the electromagnet 60 are two pivoted armatures

93 and 94 normally held from the magnet core by means of springs 95. Armature 93 in its "out" position engages stationary contact 96, from this point the circuit passing over wire 97 to wire 27 and then, as previously indicated in connection with the burglar alarm, to the code motor 3 and the transmitter 7. The pivot point of the armature 93 is connected through the hand switch 98, wire 99 to the wire 26 connecting with the secondary of power transformer 12. This completes a power circuit to the motor and transmitter. Armature 94 engages contact 100 through which the circuit passes by wire 101 to the brush 102 engaging the toothed periphery of code wheel 91, the circuit then passing through the hub 36 to the end contact 37 and thence to the modulator circuit as in the parallel burglar alarm arrangement. The pivot point of armature 94 is connected through wire 103 to the circuit 54, passing through the oscillator tube 52 of the transmitter.

As in the case of the burglar alarm, the armatures 93 and 94 are engaged by the core 92 of the magnet 60, thus holding the contacts 96 and 100 open. When the gas detector device, however, functions to open the short circuit the increase of resistance occasioned by the shifting of the current through the electromagnet 74 is sufficient to produce a release of armatures 93 and 94, resulting in closing the transmitting and code sending circuits, whereupon, by virtue of the message of the toothed code on the periphery of wheel 91 there is transmitted signals to the central station, indicating the location of and the presence of gas leakage in the building where the signalling system is located.

My safety alarm system also includes means for notifying a central station of the presence of fire in a building. This fire alarm circuit is also connected in parallel to the power transformer 12 and includes a closed circuit passing through a thermostatic device sensitive to the presence of heat. As in the burglar alarm and gas detection device, I utilize an electromagnet 105 having a core 106 projecting from either end and provided with pivoted armatures 107 and 108, each being positioned adjacent opposite ends of the core 106. Springs 109 normally hold these armatures away from the core and engagement with contacts, armature 107 being adapted to engage contacts 109 and 110, and armature 108 being adapted to engage contact 111. Movement of these armatures toward the core of the electromagnet separates them from the contacts. Contact 109 is connected to the motor and transmitter circuit 30 by wire 112. Contact 110 passes through the manual switch 115, electric bell 113 and wire 114 to the transmitter and motor circuit 31. The pivot point of armature 107 is connected through wire 116 to the main wire 11. Contact 111 of armature 108 is connected through wire 117 to the brush 118 of code disc 119 and thence to the shaft 36. The pivot point of armature 108 is connected through wire 120 to the oscillator circuit 54.

The electromagnet 105 is energized by a closed circuit passing through the heat responsive device 121 and including circuit wires 122 and 123 connecting to the secondary of transformer 12. Also, the magnet connects through wire 124 to the other terminal of the secondary of transformer 12, thus completing a normally closed circuit in parallel with the burglar alarm and gas detecting circuits.

The heat responsive means 121 may be in the nature of a fuse or, as shown, a thermostatic

device comprising two metal strips 125 and 126, preferably of brass and manganese steel, having different coefficients of heat expansion when heated by the passage of current through the strips. These strips are mounted as a unit with their flat sides adjacent each other, one end of the unit being fixed on a permanent base and the other end being movable. The free end of the unit carries a contact 127 which is adapted to engage a fixed contact 128 adjustable by means of the set screw 129. Normally the contacts 127 and 128 are in engagement, but when the strips 125 and 126 are heated by the presence of fire at a point nearby, relative expansion of the strips forces the contacts 127 and 128 apart, thus breaking the closed circuit through the electromagnet and releasing the armatures 107 and 108. Thereupon the code disc motor and radio transmitter are energized together with the oscillator circuit from the code wheel, sending the signal to the receiving station indicating the presence of fire at the location of the signalling apparatus.

In electrical apparatus of the type hereinabove described the possibility constantly exists that due to breakdown in the generating station or in the transmission lines a temporary failure of the electrical power results. When the line potential in this manner temporarily drops or is broken, though even for a brief time interval, the various electromagnets of the signalling circuits become de-energized and the code signals become immediately operative when the line voltage is restored. While the transmission of a triple signal from a building to a central station would, generally speaking, indicate a breakdown in the signalling apparatus due to the presence of three signals simultaneously, nevertheless such an occurrence is undesirable, involving unnecessary expense and attention. Accordingly, I have devised a mechanism by means of which it is possible automatically to rectify this difficulty and restore the various circuits to their original condition after the magnets of the signalling circuits have been de-energized by a temporary break in the line circuit. This mechanism includes means for restoring the movable armatures of the various electromagnets 18, 60 and 105, but is shown applied to the electromagnet 18 at the lower right hand side of the drawing in Fig. 2. Here it will be observed the electromagnet 18 is shown in perspective with its core 19 adjacent the cooperating armatures 20 and 21. Pivotedly positioned on fixed supports adjacent each of the armatures 20 and 21 are arms 130 and 131. The inner ends of these arms are connected by means of three pivotally connected bars 132, 133 and 134 which form with the arms 130 and 131 a toggle joint. The central bar 133 is provided with an elongated recess or opening 135 in which is seated the flattened end 136 of a rod 137. This rod carries a contact-making arm 138 and the armature 139 of an electromagnet 140. The rod 137 is fixedly mounted in relation to the bar 133 and the toggle joint so that when the rod rotates its action is to elongate or retract the toggle and move the arms 130 and 131 either toward the armatures 20 and 21 or away from them. Normally the toggle is open with the weighted portion of the armature 139 held downwardly by gravity. However, when energized by the electromagnet 140 the armature is moved in relation to the electromagnet, thus rotating the rod 137, lengthening the toggle and forcing the armatures 20 and 21 into contact with the ends

of the electromagnet core 19. Armature 139, as illustrated, has diminished mass in its upper part normally adjacent the electromagnet. This permits the base portion of the armature to act as a pivoting weight and insure rotation when the armature rotates to include greater energy from the electromagnet, in accordance with well-known laws of magnetism. Rotation of the rod 137 by the armature 139 causes movement of the contact-making arm 138 in a direction to bring spring contact 141 into engagement with fixed contact 142 for a purpose hereinafter described. This automatic signal-restoring mechanism includes also the electromagnet 143 having an insulated contact 144 on the end of the core 145. An armature 146 carrying a contact 147 is positioned so as to permit engagement of contacts 144 and 149. A spring 148 tends to retain armature 146 out of engagement of the contact 144 and in engagement with contact 149.

Circuits energizing the signal restoring mechanism include the wire 150 connected to the main wire 10 and passing through the electromagnet 143 to the junction point 151 where wire 152 connects to the contact 144, and wire 153 connects to the spring contact 141. The circuit continues from contact 142 through wire 154 to junction point 155 where one branch leads through wire 156 to the main wire 11. The other branch 157 is connected to the armature 146. From contact 149 connection is made to wire 150 through wire 158, electromagnet 140 and wire 159.

The operation of the signal-restoring mechanism may now be described. In the event that the line voltage drops to zero or to an extent that electromagnet 18, for example, releases armatures 20 and 21, as previously described, circuits will be closed which, as soon as the line voltage is restored, will cause signals to be sent out indicating possible burglary in the building where the apparatus is installed. Prior to the failure of the line voltage a closed circuit will have been established from the main circuit 10 through wire 150, electromagnet 143, contacts 144 and 147, wires 157 and 156 to the main 11. The circuit through the electromagnet 140 is open and the toggle joint mechanism is also open. When the line voltage drops electromagnet 143 is de-energized, permitting armature 146 to break the circuit through contacts 147 and 144, closing the circuit through contact 149 and the electromagnet 140. When the line voltage is reestablished the shaft 137 is rotated, the toggle arms 130 and 131 restoring the armatures 20 and 21 into engagement with the magnet core 19 and at the same time arm 138 closing the contacts 141 and 142. Closure of these last mentioned contacts permits the flow of current through the electromagnet 143 which draws down the armature 146, again restoring the original circuits. There is thus accomplished a complete restoration of the signalling circuits without transmission of signals due to the breakdown of the line voltage.

In order to restore the armatures of the various electromagnets 60, 105, to contact position against the respective magnet cores, after release during a signal, a toggle mechanism similar to that shown applied to magnet 18 is employed. The shaft 137 has a groove 160 on the armature end adapted to receive a key for manual rotation of the shaft, bringing the arms 130 and 131 against the armatures and moving them back to pre-signal position. In the case of magnet 18

a short circuit 161 having a key controlled switch 162 could be used to operate the armatures 20 and 21.

In the claims the terms "primary," "secondary" and "tertiary" applied to the circuits indicate respectively the transmitter and code device circuit, the electromagnet signal circuits, and the automatic signal-restoring circuit.

While I have described the application of the various devices and circuits to certain specific uses, other adaptations and uses and modifications may be made provided such come within the scope of the claims hereto appended.

I claim as my invention:

- 15 1. A safety alarm system comprising a transmitter, a signal device, means for operating said device, an electromagnet, armatures for said electromagnet, means for moving said armatures, circuits controlled by said armatures for energizing said transmitter and device operating means, a circuit including said electromagnet adapted when the current therein is diminished to permit movement of said armatures to energize the transmitter and device operating means, a source of electric power for said circuits, and second means for moving said armatures, said second means comprising lever mechanism for moving said armatures, a movable core attached to said mechanism; a magnet for moving said core, and additional means for energizing said core moving magnet when the voltage of said electric power source diminishes to a point where the armatures are actuated to close the circuits through the transmitter and device operating means.
- 30 2. A safety alarm system comprising a transmitter, a signal device, means for operating said device, an electromagnet, armatures for said electromagnet, means for moving said armatures to open and closed positions, circuits closed by the opening of said armatures for energizing said transmitter and device operating means, a circuit including said electromagnet adapted when the current therein is diminished or broken to permit movement of said armatures to open position to energize the transmitter and device operating means, a switch in said electromagnet circuit, a source of electric power for said circuits, and second means for moving said armatures to closed positions effective after a diminution of voltage of the power source and subsequent opening of the armatures without opening of the electromagnet circuit switch, said second means comprising lever mechanism for moving said armatures, a movable core attached to said mechanism, a magnet for moving said core, and an additional magnet connected in parallel with said core moving magnet adapted for energization for breaking the circuit in the core moving magnet when the voltage of the power source resumes its normal value after diminution in value.

- 35 3. In a safety signal system the combination of a transmitter, a device, primary circuits including said transmitter and device, an electric power source connected to said primary circuits, secondary circuits connected to said primary circuits, means in said secondary circuits susceptible to either disconnection or diminution of voltage in the circuits for energizing said primary circuits, tertiary circuits, and means in said tertiary circuits effective to open said primary circuits when the primary circuit is closed through a temporary diminution of current in the secondary circuit without a disconnection of the secondary circuit.
- 40 4. In an electrical system, the combination of

a first unit normally operative for sending signals on interruption of a closed circuit and a second unit for making ineffective the signalling function of said first unit when the voltage of the power source is temporarily diminished, said first unit comprising a transmitter, a signal device, means for operating said device, an electromagnet, armatures for said electromagnet movable to open and closed positions, means for moving said armatures to open position, circuits controlled by said armatures for energizing said transmitter and device operating means, a circuit including said electromagnet adapted when the current therein is diminished to permit movement of said armatures to energize the transmitter and device operating means, and a source of electric power for said circuits and said second unit comprising means for moving said armatures to closed position whereby the signalling action of the first unit is temporarily interrupted.

45 5. In an electrical system, the combination of a first unit normally operative for sending signals on interruption of a closed circuit and a second unit for preventing operation of the signal sending unit when the voltage of the supply source is temporarily diminished, said first unit comprising a transmitter, a signal device, means for operating said device; an electromagnet, armatures for said electromagnet movable to open and closed positions, means for moving said armatures to open position, circuits controlled by said armatures for energizing said transmitter and device operating means, a circuit including said electromagnet adapted when the current therein is diminished to permit movement of said armatures to open position to energize the transmitter and device operating means, a source of electric power for said circuits and said second unit comprising means for moving said armatures to closed position, said means including an electromagnet, a core movable by said electromagnet, and lever mechanism secured to said core for mechanically moving said armatures.

50 6. In a safety alarm system a power source normally operable at a given voltage but susceptible to chance decreases of voltage, an electromagnet having a core connected in circuit with said power source, an armature, a signal circuit connected to said armature, the movement of the armature to displaced open position closing said signal circuit, a signal device in said signal circuit, a transmitter connected to the signal device, means for yieldably holding said armature displaced from said core, mechanism for moving said armature into contact with said core to be retained thereby during the energization of the electromagnet, and electrical means effective only after a drop in the voltage of the power source to a point where the armature is released from the magnet core for operating said mechanism to recontact the armature and core when the voltage of the power source has acquired its normal value after a decrease in value.

55 7. In a safety alarm system a power source normally operable at a given voltage but susceptible to chance decreases of voltage, an electromagnet having a core connected in circuit with said power source, an armature, a signal circuit connected to said armature, the movement of the armature to displaced open position closing said signal circuit, a signal device in said signal circuit, a transmitter connected to the signal device, means for yieldably holding said armature displaced from said core, mechanism for moving said armature into contact with said core

to be retained thereby during the energization of the electromagnet, and electrical means effective only after a drop in the voltage of the power source to a point where the armature is released
5 from the magnet core for operating said mechanism to re-contact the armature and core when the voltage of the power source has acquired its normal value after a decrease in value, said electrical means including a movable core, a second
10 electromagnet adapted to move said movable core, and a third electromagnet, said second and third electromagnets being connected in physical parallel with each other, and switching means for energizing only one of said second and third magnets at a time.
15

8. In a safety alarm system a power source normally operable at a given voltage but susceptible to chance decreases of voltage, an electromagnet having a core connected in circuit
20 with said power source, an armature, a signal circuit connected to said armature, the movement of the armature to displaced open position closing said signal circuit, a signal device in said signal circuit, a transmitter connected to the
25 signal device, means for yieldably holding said armature displaced from said core, mechanism including lever arms and shaft for moving said armature into contact with said core to be retained thereby during the energization of the
30 electromagnet, and electrical means effective only after a drop in the voltage of the power source to a point where the armature is released

from the magnet core for operating said mechanism to recontact the armature and core when the voltage of the power source has acquired its normal value after a decrease in value, said electrical means including a movable core, a second 5 electromagnet adapted to move said movable core, and a third electromagnet, said second and third electromagnets being connected in physical parallel with each other, and switching means for energizing only one of said second and third 10 magnets at a time, said switching means comprising an armature for said third magnet, contacts on either side of, and spaced from, said armature, two normally open spring contacts adjacent said armature mechanism shaft, a lever 15 arm secured to the shaft adapted to close said spring contacts when said third magnet armature is energized, and circuits intermediate said spring contacts, said second and third electromagnets and power source adapted normally to 20 energize the third magnet only and retain the armature of the third electromagnet in contact with one of its contacts and when the line voltage is diminished to release the armature of the third electromagnet to close the circuit through 25 the other contact, second electromagnet and spring contacts whereby the lever mechanism is operated to force the first named armature into contact with the core of the first electromagnet on the restoration of the line voltage. 30
